UNITED STATES PATENT OFFICE.

JOHN CARNEY, OF WALTHAM, MASSACHUSETTS.

ENGINE AND GEAR CASING.

SPECIFICATION forming part of Letters Patent No. 772,214, dated October 11, 1904.

Application filed February 11, 1904. Serial No. 193,172. (No model.)

To all whom it may concern:

Be it known that I, JOHN CARNEY, a citizen of the United States, residing at Waltham, in the county of Middlesex and State of Massachusetts, have invented certain new and useful Improvements in Engine and Gear Casing; and I do declare the following to be a full, clear, and exact description of the invention, such as will enable others skilled in the art to which it app-
10 pertains to make and use the same.

This invention relates to improvements in casings for the engine and gearing of automobiles and the like.

The object of the invention is to provide a
15 casing for this purpose which will protect the parts covered thereby from dust, dirt, or any foreign matter which would interfere with the perfect working of the parts.

Another object is to provide a casing for
20 this purpose the connections of which will permit the parts to yield with the movement of the gearing and which will not rattle when jarred by the motion of the machine.

A further object is to provide a case of this
25 character formed in separate sections for covering the different parts of the gearing and engine, each section of which may be removed without disturbing the other parts.

With these and other objects in view the invention consists of certain novel features of construction, combination, and arrangement of parts, as will be more fully described, and particularly pointed out in the appended claims.

In the accompanying drawings, Figure 1 is
35 a side elevation of the complete casing, showing the arrangement of the connected sections. Fig. 2 is a longitudinal vertical sectional view of the same. Fig. 3 is a side elevation showing the sections detached. Fig. 4 is a detail
40 vertical sectional view through the meeting edges of the engine and the chain-casing, showing the manner of fastening the two together.

Referring more particularly to the drawings, 1 denotes the casing, which is preferably constructed of leather and in three parts—to wit, an engine-case 2, a sprocket-chain case 3, and a sprocket-wheel case 4. The engine-case 2 consists of a leather covering which preferably conforms somewhat to the shape
50 of the engine and is supported by straps 3' to

a fixed part of the frame which supports the engine. The front side of the engine-case is open, and in front of the same is arranged a curtain 2', of leather or other suitable material. In the side of the casing are formed 55 openings 5, through which the engine may be oiled. These openings are normally closed by pivoted cover-plates 5'. The rear side or end of the engine-casing where the chain-covering connects is left open to permit the passage of the sprocket-chain from the drive-wheel on the engine to the sprocket-wheel on the axle, and in the sides of the engine-casing adjacent to this opening are formed a series of horizontally-disposed parallel slots 6. 60

The chain-covering consists of a tapering open-ended case 3, the top or upper wall of which is removably secured to the side walls by strap - and - buckle connections 7. The smaller end of the casing 3 is adapted to be 65 inserted into the chain-opening of the engine-casing, and the sides of the same are provided with a series of laterally-projecting studs 8, in which are formed openings or eyes 9. These studs 8 are adapted to engage and 70 pass through the slots 6 in the sides of the engine-casing, after which a pin 10 is inserted through the eyes or openings 9 in the studs 8, thereby securing the end of the chain-casing with the engine-casing, the slots 6 permitting 75 a slight play between the two casings to compensate for the movement of the gearing.

In the sides of the casing, at the large end of the same, are formed aligned semicircular recesses 12, which allow for the passage of 80 the vehicle-axle. To the sides of the chain-casing above and below the recesses 12 are secured straps 13. To the end of the bottom of the chain-casing is secured a flap 14, on the end of which is fixed a strap 15. In the ends 85 of the side walls of this casing, near the lower edges of the same, are formed slots 16.

The sprocket-wheel covering consists of a segmental-shaped casing 4, the flat side 4' of which is open and adapted to fit within the 90 larger open end of the chain-casing and is held in place therein by means of the straps 13, which engage buckles 17 on the sides of the sprocket-casing, and by a strap 15, which engages a buckle 18 on the outer edge of said 95 100

casing and holds the flap 14 up against the under side of the casing, as shown.

In the side walls of the sprocket-casing are formed centrally-disposed alined holes 19 to 5 permit the passage of the vehicle - shaft through the same. The sides of the casing are cut out to form passages 20 between the inner edge of the same and said holes to permit the casing to be arranged over the 10 sprocket-wheel. Said sides are also provided with slots 21, which open through the inner edge of the casing and which when the end of this casing is inserted into the end of the chain-casing will aline with the slots 16 to 15 form openings for the passage of truss or brace-rods.

In constructing a casing as herein described of independent sections it will be seen that any one of the same may be removed without 20 removing the others and that, if so desired, only a part of the sections need be used. For instance, an engine may be already provided with a casing, in which event simply the chain and sprocket-wheel casings would be used.

25 In forming the casings of leather or similar flexible fabric all noise which would be occasioned by the shaking or rattling of the parts if constructed of metal will be obviated. Furthermore, the parts of the casing when formed 30 of leather may be readily cut and made to fit various formations in the construction of the engine and gearing, and while a form of casing is shown in the drawings for a particular design of engine it is obvious that the shape 35 of the casing may be altered to fit any form of engine and gearing that it may be desired to inclose.

From the foregoing description, taken in connection with the accompanying drawings, 40 the construction and operation of the invention will be readily understood without requiring a more extended explanation.

Various changes in the form, proportion, and the minor details of construction may be 45 resorted to without departing from the principle or sacrificing any of the advantages of this invention.

Having thus described my invention, what I claim as new, and desire to secure by Letters 50 Patent, is—

1. An engine and gear casing comprising,

an engine - covering, a chain - cover, and a sprocket-wheel covering, and means for removably connecting said coverings together to form a complete casing for said parts, substantially as described. 55

2. An engine and gear casing comprising independently-formed sections for covering an engine, a sprocket-chain and a sprocket-wheel, means whereby said engine and chain-sections are connected together to have a sliding engagement one with the other, means for removably connecting the opposite end of said chain-section with said sprocket-wheel section, substantially as described. 60

3. An engine-casing having an opening, a chain-casing adapted to enter said opening, and means for connecting the two casings together.

4. An engine-casing having an opening, the 70 walls of which are provided with slots, a gear-casing entering said opening and provided with lugs to project through said slots, and means for engaging the lugs to hold the same in engaged position.

5. An engine-casing having an opening, the walls of which are provided with slots, a chain-casing provided with studs to pass through 75 said slots, and pins adapted to be passed through said studs to hold the two casings connected.

6. An engine-casing provided in its front and rear walls with openings, a closure for the front opening, a chain - casing entering the rear opening, and means for connecting the 85 two casings together.

7. An engine-casing provided with an opening, a chain-casing open at each end and having one end inserted within the opening in the engine-casing, a gear-casing adapted to fit 90 within the opening in the opposite end of the chain-casing, the casings thus being telescopically connected, and means for detachably connecting the casings together.

In testimony whereof I have hereunto set 95 my hand in presence of two subscribing witnesses.

JOHN CARNEY.
